CLAIM

The ornamental design for a mobile cleaning robot, as shown and described.

DESCRIPTION

FIG. 1 is a top-left-perspective view of our mobile cleaning robot;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof;

FIG. 8 is a bottom-left-perspective view;

FIG. 9 is a top view thereof showing the designated portions for enlarged detail view of FIGS. 10 and 11; and

FIG. 10 is an enlarged detailed view of the designated 10 of FIG. 9; and

FIG. 11 is an enlarged detailed view of the designated 11 of FIG. 9.

FIG. 12 is a top-left-perspective view of our mobile cleaning robot;

FIG. 13 is a front view thereof;

FIG. 14 is a rear view thereof;

FIG. 15 is a left-side view thereof;

FIG. 16 is a right-side view thereof;

FIG. 17 is a top view thereof; and

FIG. 18 is a bottom view thereof;

FIG. 19 is a bottom-left-perspective view;

FIG. 20 is a top view thereof showing the designated portions for enlarged detail view of FIGS. 10 and 11; and

FIG. 21 is an enlarged detailed view of the designated 21 of FIG. 20; and,

FIG. 22 is an enlarged detailed view of the designated 22 of FIG. 20.

The broken lines shown in the figures are for the purpose of illustrating portions of the mobile cleaning robot and form no part of the claimed design.

(Continued)

The broken lines encircling portions of the claimed design that are illustrated in the enlargements form no part of the claimed design.
